US0D1038449S

(12) **United States Design Patent** (10) Patent No.: **US D1,038,449 S**
(45) Date of Patent: ** Aug. 6, 2024

(54) **MOTION SENSOR LIGHT**

- (71) Applicant: **Perch Acquisition Co. 36, LLC**,
Boston, MA (US)
- (72) Inventor: **Brian P. Johnson**, Dallas, TX (US)
- (73) Assignee: **Perch Acquisition Co. 36, LLC**,
Boston, MA (US)

(**) Term: **15 Years**

(21) Appl. No.: **29/875,888**

(22) Filed: **May 12, 2023**

CLAIM

The ornamental design for a motion sensor light, as shown and described.

DESCRIPTION

FIG. 1 is a perspective view of a motion sensor light showing my design, as viewed from the top and front.

FIG. 2 is a front profile view thereof.

FIG. 3 is a back profile view thereof; and,

FIG. 4 is a side profile view thereof.

The broken lines in the drawings illustrate portions of the motion sensor light that form no part of the claimed design.
